(57) **CLAIM**

The ornamental design for an animal feeder as shown and described.

DESCRIPTION

FIG. 1 is a front perspective view of the animal feeder in a closed position;

FIG. 2 is a front perspective view of the animal feeder in an open position;

FIG. 3 is a front view of the animal feeder;

FIG. 4 is a side view of the animal feeder; and,

FIG. 5 is an enlarged detail view of FIG. 1, showing an enlarged portion for clarity of illustration.

The broken lines depict portions of the animal feeder that form no part of the claimed design.

1 Claim, 5 Drawing Sheets
